UNITED STATES PATENT OFFICE.

BICKNELL HALL, OF TAUNTON, MASSACHUSETTS, ASSIGNOR OF ONE-THIRD
TO EDWARD P. COLEMAN, OF SAME PLACE.

TUBE FOR USE IN EXPANSION-JOINTS.

SPECIFICATION forming part of Letters Patent No. 530,305, registered December 4, 1894.

Application filed August 24, 1894. Serial No. 521,255. (No model.)

To all whom it may concern:

Be it known that I, BICKNELL HALL, of Taunton, in the county of Bristol and State of Massachusetts, have invented a new and useful Improvement in Tubes for Use in Expansion-Joints, so-called, Condensers and Feed-Water Heaters, and the Like, of which the following is a specification.

My invention is an improvement on the corrugated tube which has been extensively used under the circumstances referred to to take up the expansion and contraction due to changes of temperature.

From long experience I have found that when a piece of corrugated tubing is constantly expanding and contracting a very large percentage of the bending due to expansion and contraction falls upon those corrugations which are weaker or thinner than the others so that the wear is not distributed equally and the tube wears out sooner than it should.

My invention is intended to remedy this fault and it consists in a piece of tubing which is not corrugated but is indented in lines across the axis of the tube by a series of short indentations which are so arranged that each indentation breaks joints with the indentations on each side of it and is separated at each end from the next indentation in line by a blank space, the natural curvature of the tube.

My invention will be understood by reference to the drawings, in which—

Figure 1 is an elevation partly in section of a piece of tubing embodying my invention, Fig. 2 being a cross section on line 2 of Fig. 1.

A represents the indentations above described, B being the portions of plain tube lying between the ends of the indentations and C being those portions of the plain tube which lie between the lines of indentations. In cross section these indentations are preferably curved as will be understood from Fig. 1, but the length of each indentation is less than the circumference of the tube so that each indentation extends only part way

round the tube. In the drawings each indentation is somewhat less in length than a quarter of the circumference of the tube and each indentation breaks joints so to speak, with the indentations in the line next it on each side. By this means I find that the strain tending to change the length of these tubes is distributed very evenly throughout the length of tube.

The number of indentations may well depend upon the diameter of the tube or upon the thickness of the metal, and the "lines" of indentations may be annular as shown or a spiral line of indentations may be used, with substantially the same result. I prefer for general use however, the annular indentations, four in number as shown.

Such a tube as I have described may be made upon a collapsible grooved mandrel which is set up in a turning lathe so as to be rotated. The tool is an ordinary roller of proper dimensions to form the indentation, a portion of the periphery of the tool being removed so as to leave the part B of the tube untouched. This tool is mounted in a tool stock in the ordinary way and held against the tube.

The process of manufacture will be easily understood in all its details by those skilled in tube working.

What I claim as my invention is as follows:

1. The tube above described provided with a series of indentations lying in a line or lines across the axis of the tube, each indentation being less in length than the circumference of the tube, as set forth.

2. The tube above described provided with a series of indentations arranged in a line or in lines across the axis of the tube, each indentation being separated from the indentation at each end of it and breaking joints with the indentations at each side of it, as set forth.

In testimony whereof I have hereunto set my hand this 14th day of August, 1894.

BICKNELL HALL.
